UNITED STATES PATENT OFFICE.

GILES M. G. MAKIN, OF PAWTUCKET, RHODE ISLAND.

LACE-MACHINE CARRIAGE.

Application filed January 29, 1925. Serial No. 5,485.

To all whom it may concern:

Be it known that I, GILES M. G. MAKIN, a citizen of the United States of America, residing at Pawtucket, in the county of Providence and State of Rhode Island, have invented certain new and useful Improvements in Lace-Machine Carriages, of which the following is a specification.

This invention relates to improvements in lace machine carriages.

An important object of the invention is to provide a lace machine carriage having a self threading tensioning portion.

A further object of the invention is to provide a carriage of the above mentioned type wherein tension is brought to bear upon the thread after it leaves the bobbin and the latter is left to freely rotate in the cage or opening of the carriage.

A still further object of the invention is to provide in a lace machine carriage means adapted for performing the combined functions of placing tension upon the thread after it leaves the bobbin and for guiding and holding the bobbin within the carriage, it being noted, however, that said means does not frictionally bear against or retard the free rotation of the bobbin.

Another object of the invention is to provide means for removably locking a bobbin in a lace machine carriage to permit free rotation of the bobbin, but preventing it from being displaced laterally out of alignment with the carriage.

Other objects and advantages will be apparent during the course of the following description.

In the accompanying drawings forming a part of this specification and in which like numerals are employed to designate like parts throughout the same,

Figure 1 is a plan view of one form of lace machine carriage embodying this invention,

Figure 2 is a plan view of the opposite side of the carriage illustrated in Fig. 1,

Figure 3 is a transverse sectional view taken upon line III—III of Fig. 2,

Figure 4 is a plan view of a modified form of carriage embodying this invention,

Figure 5 is a sectional view taken upon line V—V of Fig. 4,

Figure 6 is a detail edge view of the bobbin guiding and thread tensioning portion of the carriage shown in Figs. 1 to 3 inclusive,

Figure 7 is a sectional view of the outer

portion of the carriage shown in Figs. 1 to 3 inclusive,

Figure 8 is a fragmentary perspective view of the bobbin holding and thread tensioning portion of the carriage shown in Figs. 1 to 3 inclusive and further illustrates the manner of threading the tensioning portion of the carriage,

Figure 9 is a similar view to Fig. 8, but taken to illustrate the opposite side thereof,

Figure 10 is an enlarged sectional view taken upon line X—X of Fig. 2,

Figure 11 is a fragmentary plan view of a further modified form of bobbin holding and thread tensioning means, and

Figure 12 illustrates a plan and edge elevational view of the pivotal element shown in Fig. 11.

Referring to the accompanying drawings and particularly to Figs. 1 to 3 inclusive and 6 to 9 inclusive, the numeral 5 designates the carriage having the bobbin opening or cage 6 formed therein within which the bobbin 7 travels. By examining Fig. 3, it will be seen that the bobbin is of the double side or disk type having the said sides or disks 8 suitably held together and spaced for permitting the winding of thread therebetween. In Fig. 7, the outer portion of the carriage opening 6 is illustrated as being provided with a guiding rib 9 which projects between the said sides or disks 8 of the bobbin for holding the latter in alignment with this portion of the carriage.

The inner edge portion of the carriage 5 is partially cut through or recessed at 10 for receiving the lever 11 which is pivotally secured at 12 to the carriage. This lever includes an arm 13 which extends substantially circumferentially of the bobbin 7 and is provided with an inwardly projecting keel or guide 14 which is adapted for being located between the sides or disks of the bobbin for maintaining the latter in place within the bobbin opening or cage and for insuring against the lateral displacement of the said bobbin. This keel or guide 14 is retained between the sides or disks of the bobbin by the spring 15 which is secured, as illustrated, to the carriage 5. In Fig. 8, the outer face of the lever arm 13 is illustrated as being provided with a longitudinally extending groove 16 which receives a lug or tip carried by the underface 110 of the free end of the spring 15. The partially cut through or recessed portion 10

formed in the inner side portion of the carriage 5 is best illustrated in Fig. 9 as forming a shoulder 17 against which the outer edge 18 of the plate-like backing member 19 bears, the function performed by this plate-like backing member being clearly disclosed at a later point.

The self-threading tensioning portion of the form of carriage now being described is best illustrated in Figs. 1 and 8 and includes the thread hole 20 formed in the carriage 5. The arm 21 is formed as an extension of one side wall of the thread hole 20 and has its outer end 22 reduced in transverse thickness. The remaining side wall of the thread hole 20 terminates at 23 in a thread confining projection which is slightly spaced from the adjacent edge of the arm 21 and resides in the same plane therewith. It will now be seen that the plate-like backing 19 overlies or extends in parallelism with the arm 21 and thread confining projection 23 and is arranged in close proximity to the same.

In Fig. 8 the self-threading feature of the tensioning means is illustrated by the showing of the thread T at several stages during the threading operation. The thread T is shown in full lines prior to the threading of it into the tensioning means. The thread, at a point spaced from the bobbin, not shown in Fig. 8, is grasped by the operator and the thread moved in the direction of the dotted line positions. This lateral movement of the thread causes the same to pass in back of the arm 21, due to its thinned end 22, and around the thread confining projecting 23 until it is received within the thread opening 20. The thread then passes between the plate-like backing 19 and the arm and projection 21 and 23 respectively. The slight pinching of the thread, brought about by the members 19, 21 and 23, will place the proper tension on the former.

The carriage 5^a of the form shown in Figs. 4 and 5 is very similar to the carriage 5 shown in the previously referred to figures, the only difference in construction occurring at the thread tensioning portion. For this reason, the differences in construction will be pointed out and the similar features will not be specifically referred to, but will bear the same reference numerals as those disclosed in connection with the first form of carriage.

The carriage 5^a is entirely cut through at 10^a and forms the shoulder 17^a against which the edges of the removable plate-like backing 19 and the arm and thread-hole carrying portion to which the plate-like portion 19^a is secured. The lever 11^a is pivoted to the carriage at 12^a and has formed there in the arm 21^a and the thread-hole 20^a, the thread confining projection 23^a also being

carried thereby and associated with the arm 21^a and the hole 20^a in the same manner as described in connection with the thread confining projection 23 in the first form of the invention.

It will be understood that this carriage with its bobbin holding and thread tensioning means functions in the same manner as described in connection with the form of the invention shown as Figs. 1 to 3 inclusive 75 and 6 to 9 inclusive.

A further form of the invention is shown in Figs. 11 and 12 and includes the carriage 5^b which is partially cut through or recessed at 10^b to form the plate-like backing 19^b 80 and the shoulder 17^b. The lever 11^b is pivoted at 12^b to the carriage and is formed with the arm 21^b, the thread hole 20^b and the thread confining projection 23^b as illustrated. The portion of the lever provided 85 for engaging the shoulder 17^b formed on the carriage 5^b to limit the pivotal movement of the lever 11^b includes the shoulder or flange 18^b, best illustrated in Fig. 12. It is to be understood that this form of the 90 invention functions similarly to the forms previously described.

I am desirous of having it clearly understood that the thread is tensioned after leaving the bobbin and the latter is permitted to freely rotate in the cage or opening of the carriage. The pivoted member in the various forms of the invention illustrated in the accompanying drawings are specifically referred to as including an arm 100 portion provided with a keel which is adapted for being received between the sides or disks of the bobbin for holding the latter in place to prevent lateral displacement of the same. The various forms are also 105 referred to as including the shoulder portion against which one end of this pivoted member or lever bears to limit the pivotal movement of the said member. The arm portion of the lever is also referred to as failing to 110 forcibly engage the periphery of the bobbin, thereby permitting the latter to rotate freely. By carefully examining Fig. 2, it will be seen that the bobbin 7 is of a proper diameter to clear the arm 13 at its periphery although the keel portion 14 of the arm 13 projects into the space between the sides or disks of the said bobbin. The pivotal movement of the arm 13 toward the periphery of the bobbin 7 is limited by the 115 opposite end of the pivoted member or lever engaging the shoulder 17. It is now believed that the structure which permits the free rotation of the bobbin without the placing of any tension thereupon will be clearly 120 understood.

It is to be understood that the forms of this invention herewith shown and described are to be taken as preferred examples of the same, and that various changes in the 125 130

shape, size, and arrangement of parts may be resorted to without departing from the spirit of the invention or the scope of the subjoined claims.

5 Having thus described the invention, I claim:—

1. In a device of the class described, a carriage having a bobbin opening, a bobbin traveling in said opening, a pivoted mem-

10 ber carried by the carriage for removably holding the bobbin in the opening and guiding it against lateral displacement in respect to the carriage, and a spring element for retaining the pivoted member in its operative position.

2. In a device of the class described, a carriage having a bobbin opening, a bobbin traveling in said opening, a pivoted mem-

15 ber carried by the carriage for removably holding the bobbin in the opening and guiding it against lateral displacement in respect to the carriage, a spring element for

20 retaining the pivoted member in its operative position, and means for preventing the pivoted member from forcibly bearing

25 against the bobbin.

3. In a device of the class described, a carriage having a bobbin opening, a bobbin traveling in said opening, a pivoted mem-

30 ber carried by the carriage for removably holding the bobbin in the opening and guiding it against lateral displacement in respect to the carriage, a spring element for

35 retaining the pivoted member in its operative position, and means for preventing the pivoted member from forcibly bearing

40 against the bobbin.

4. In a device of the class described, a carriage having a bobbin opening, a bobbin

45 traveling in said opening, a pivoted mem- ber carried by the carriage for removably holding the bobbin in the opening and guid-

50 ing it against lateral displacement in respect to the carriage, a spring element for retaining the pivoted member in its opera-

55 tive position, and a movement limiting sur-

60 face formed on the carriage and engageable by the pivoted member for preventing the latter from forcibly bearing against the

65 bobbin.

5. In a device of the class described, a carriage having a bobbin opening, a bobbin traveling in said opening, a pivoted mem-

55 ber carried by the carriage for removably holding the bobbin in the opening and guid-

60 ing it against lateral displacement in respect to the carriage, a spring element for

65 retaining the pivoted member in its opera-

70 tive position, and a stationary shoulder for preventing the pivotal member from forcibly bearing

75 against the bobbin.

6. In a device of the class described, a carriage having a bobbin opening, a bobbin

80 of the double disk type traveling in said opening, a pivotal member carried by the

carriage and projecting between the disks of the bobbin for removably holding and guiding the bobbin, a spring element for retaining the pivotal member in its opera- 70 tive position, and means for preventing the pivotal member from forcibly bearing against the bobbin.

7. In a device of the class described, a carriage having a bobbin opening, a bobbin

75 of the double disk type traveling in said opening, a pivotal member carried by the carriage and projecting between the disks

80 of the bobbin for removably holding and guiding the bobbin, and a stationary shoul-

85 der for preventing the pivotal member from forcibly bearing against the bobbin.

8. In a device of the class described, a carriage having a bobbin opening, a bobbin

85 of the double disk type traveling in said opening, a pivotal member carried by the carriage, a keel depending from one end

90 of the pivotal member and projecting be-

95 tween the disks of the bobbin for removably holding and guiding the latter, and a spring

90 bearing against the upper face of the same end of said pivotal member.

9. In a device of the class described, a carriage having a bobbin opening, a bobbin

95 of the double disk type traveling in said opening, a pivotal member carried by the carriage, a keel depending from one end

100 of the pivotal member and projecting be-

105 tween the disks of the bobbin for removably holding and guiding the latter, the upper

110 face of the same end of said pivotal mem-

115 ber having a groove formed therein, a spring

carried by the carriage and having a tip pro-

jecting into said groove, and means for pre-

venting the pivotal member from forcibly

120 bearing against the bobbin.

10. In a device of the class described, the combination with a bobbin carriage, of

125 thread tensioning means carried by the carriage, said tensioning means including an arm extending transversely to the direction

130 of travel of the thread, a projection slightly spaced from the arm, and a plate-like

135 backing in close proximity to the arm and projection, said arm, projection and plate-

140 like backing functioning to place tension on thread passing therebetween.

11. In a device of the type described, the combination with a bobbin carriage, of

145 thread tensioning means carried by the carriage, said tensioning means including an arm extending transversely to the direc-

150 tion of travel of the thread, a projection slightly spaced from and located in the same

155 plane as the arm, and a plate-like backing in close proximity to the arm and projec-

160 tion, said arm, projection, and plate-like

165 backing functioning to place tension on thread passing therebetween.

12. In a device of the type described, a carriage, a bobbin traveling therein, means

2
pivotally carried by the carriage for removably holding and guiding the bobbin and for placing tension on the thread after it leaves the bobbin, and a spring bearing 5 against said pivotal means for moving one of its ends toward said bobbin.

13. In a device of the type described, a carriage, a bobbin traveling therein, means pivotally carried by the carriage for removably holding and guiding the bobbin and for placing tension on the thread after it leaves the bobbin, a spring bearing against 10 said pivotal means for moving one of its ends toward said bobbin, and means for limiting the pivotal movement of the first mentioned means.

14. In a device of the type described, a carriage, a bobbin traveling therein, means pivotally carried by the carriage for removably holding and guiding the bobbin and for placing tension on the thread after 20 it leaves the bobbin, a spring bearing against said pivotal means for moving one of its ends toward said bobbin, and a shoulder formed on said carriage for limiting the 25 pivotal movement of the first mentioned means.

15. In a device of the type described, the combination with a bobbin carriage, of a 30 threading device pivotally carried by said carriage, said threading device having a thread-hole, and including means for guiding thread into said hole.

16. In a device of the type described, the combination with a bobbin carriage, of a 35 threading device pivotally carried by said carriage, said threading device having a thread-hole formed with its axis extending at right angles to the plane of the carriage, and an arm formed as an extension of the 40 wall of the hole and extending longitudinally of the device for guiding the thread into said hole.

17. In a device of the type described, the

combination with a bobbin carriage, of a 45 threading device pivotally carried by said carriage, said threading device having a thread-hole provided with a thread entrance, an arm formed as an extension of the wall 50 of the hole for guiding thread through said entrance, and means for confining thread in said hole.

18. In a device of the type described, a carriage, a bobbin traveling therein, and means pivotally carried by the carriage and 55 cooperating with a portion thereof for placing tension on the thread after it leaves the bobbin, said means having a thread-hole therethrough provided with a thread entrance and an arm for guiding the thread 60 into said entrance.

19. In a device of the type described, a carriage, a bobbin traveling therein, and an element pivoted intermediate its ends to said carriage, the portion of said pivoted member located to one side of said pivot point 65 acting as means for removably holding and guiding the bobbin and the portion on the opposite side of said pivot point cooperating with the adjacent portion of said carriage for placing tension on the thread after 70 it leaves the bobbin.

20. In a device of the type described, a carriage having a bobbin opening, a bobbin traveling in said opening, a pivoted member carried by the carriage for removably holding the bobbin in said opening and guiding it against lateral displacement in 75 respect to the carriage, a spring for forcing the pivoted member toward the bobbin, a shoulder carried by the carriage, and a lateral projection carried by the pivoted member and bearing against the said shoulder 80 for preventing the pivoted member from forcibly bearing against the bobbin. 85

In testimony whereof I affix my signature.

GILES M. G. MAKIN.
